Specification of Letters Patent.

Patented Oct. 14, 1913.

Application filed April 9, 1909. Serial No. 488,824.

To all whom it may concern:

Be it known that I, LOUIS A. SCHMIDT, a citizen of the United States, residing at New York, county of Kings, and State of New York, have invented certain new and useful Improvements in Printing-Machines, fully described and represented in the following specification and the accompanying drawings, forming a part of the same.

10 This invention relates to improvements in printing machines.

In the production of newspapers, the unit ordinarily employed is the four page sheet, this being the product of a pair of printing 15 and perfecting couples, the printing member of each couple being provided, to produce this unit, with two plates arranged side by side and the web being wide enough to receive the two impressions, that is each 20 printing cylinder carries four plates, these plates being arranged two around and two across the cylinder, the printing matter on what may be termed the second pair of plates varying with respect to the character 25 of paper to be produced, that is to say, the second pair of plates may carry matter which is a duplicate of the first pair of plates, or it may differ therefrom in case a collected product is to be produced. The 30 product of such a machine is ordinarily increased by increasing the length of the cylinders so as to cause the printing cylinders to carry a second set of four plates. By duplicating the sets of cylinders the product 35 may also be readily increased, the four page product, however, being the unit of increase, so that the products produced are multiples of this four page unit. It will be understood, of course, that in printing machines 40 of the character referred to, the plates may be arranged with their columns either running around the cylinders or parallel to their axes as may be desired. Where, however, the columns of the plates run around the cylinder, the usual type of folder employed is 45 the well-known longitudinal folder or former, but where the plates have their columns parallel with the axis of the cylinder, a former cannot be used, and the folder is 50 usually of the rotary type, so that the fold may be made parallel with the columns.

Where it is desired to produce a product the pages of which are not a multiple of four, such, for instance, as a six, ten, or four- 55 teen page product, it is, of course, obvious

that the four page unit cannot be employed and therefore various types of mechanism have been used, these mechanism in the main depending upon the printing of a single wide web, that is, a web wide enough to 60 carry the impression of a single plate, this single wide web being associated with a full width web to produce a six page paper, with two full width webs to produce a ten page paper, and so on, this single wide web being 65 printed either by making the cylinders long enough to carry an extra set of plates, or, as is usual, where ten and fourteen page papers are to be produced, by introducing into the machine an extra set of couples running either at full speed or at half speed.

In Patent No. 857,962, granted July 25, 1907, to Robert Hoe, as assignee of O. L. Raabe and G. F. Read, a machine is disclosed for producing products the pages of 75 which are not a multiple of four. In this machine, the printing member of each couple is arranged to carry six plates, these plates being arranged three across the cylinder and two around, the columns being 80 parallel to the axis of the cylinder. The machine prints upon a three wide web, this web being slit into three parts, sheets from which are subsequently associated and delivered by a rotary folder. This machine is construct- 85 ed so that one of the pair of printing plates on one end of each cylinder may be omitted, the blank thus left on the web, as it passes between the cylinders, being cut out and the sheet thus formed delivered as a blank sheet 90 out of the machine, the remaining sheet which contains only two pages being associated with sheets from the other webs to form what may be termed the odd sheet products. While the particular machine re- 95 ferred to and disclosed in said patent has distinct advantages, some newspaper offices desire machines in which the columns run around the cylinder rather than across, for the reason that it is sometimes desired to 100 vary the number of columns in the paper. It will, of course, be understood that where the columns are arranged parallel with the axis of the cylinder, the columns always being of standard width, the number of col- 105 umns is necessarily fixed because the plates must, to avoid wasting paper, cover substantially the entire surface of the cylinder. Further, certain newspaper offices desire to use a longitudinal folder which it is not 110

feasible to use with the particular machine disclosed in the patent referred to.

The present invention has for its object to produce an improved printing machine which shall be simple and economical to build, which shall be of such a character that papers having pages not a multiple of four may be produced, which shall be capacitated to print from plates arranged with the columns running around the cylinder and with which a longitudinal folder may be used if desired.

With this and other objects not specifically referred to in view, the invention consists in certain constructions, and in certain parts, improvements and combinations as will be hereinafter fully described and then specifically pointed out.

Referring to the drawings—Figure 1 is a diagrammatic side elevation of so much of a printing machine constructed in accordance with the invention as is necessary to an understanding thereof. Fig. 2 is a view similar to Fig. 1, showing the parts in a different position. Fig. 3 is a view similar to Fig. 1, the mechanism being, however, arranged to produce a fourteen page paper, an additional cutting mechanism being shown. Fig. 4 is a view similar to Fig. 3, but showing the parts in a different position. Fig. 5 is a plan view of certain web transferring mechanism which may be employed. Fig. 6 is a plan view of one of the printed webs used in the formation of a fourteen page product. Fig. 7 is a plan view of certain collecting and transferring mechanism employed in the machine illustrated.

It will be understood that, in carrying the invention into effect, the web or webs may be printed by printing and perfecting couples, the printing member of each couple being arranged to carry eight plates arranged four across and two around the cylinder, and with the columns of the plates running around the cylinder, or two sets of couples may be employed, the printing member of each couple carrying four plates, arranged two around and two across. The construction of rotary printing machines of the character referred to is well understood in the art, and a specific description and illustration thereof is unnecessary to an understanding of the invention. The arrangement of the plates, however, will be understood from the illustration of the printed web in Figs. 6 and 7.

Referring to the drawings, and assuming that the web marked 1 has been printed and perfected in a machine employing couples the printing member of each of which is capacitated to carry eight plates arranged four across and two around, the webs are forwarded in the usual manner and acted upon by a slitter, indicated at 2, this slitter co-operating with the usual roller, indicated

at 3. The slitter converts the web 1 into two webs, marked 4, 5, the web 5 being the one which is farthest from the observer in Fig. 1. This web, in the particular construction illustrated, is transferred laterally by the usual bars 6, 7, so as to bring it beneath the web 4, and it is then forwarded by the usual guides, indicated at 8, 9, compensating roll 10, and driven nipping rollers 11. If desired, paste may be applied to this web by rolls 12 of the usual type in this class of machines. This web may be cut into sheets in any desired manner, by mechanism which may be varied in character and location. In the particular machine illustrated, the cutting is effected by a pair of cylinders 13, 14, one of which is a collecting cylinder.

Machines embodying the invention will include means for removing a section from one of the webs in order to enable a product containing pages not a multiple of four to be formed. The means employed for thus removing this web section may be varied and will vary according to the product to be produced.

Referring more particularly to the construction illustrated in Figs. 1 and 2, the removing mechanism employed in the particular machine illustrated in these figures, includes a pair of cutting cylinders of a usual type. After the slitting operation, the web 4 is forwarded by nipping rolls 15, a compensating roll 16 being employed, if desired, to the pair of cutting cylinders 17, 18 which convert it into sheets. As has been indicated, the construction shown in Figs. 1 and 2 is arranged to produce a ten page paper and, in this instance, the web 1 is a three wide web, the slitter employed dividing this web into a single wide web 4 and a double wide web 5. One of the plates of each printing cylinder is omitted, so that the web 4 has alternately a printed page and a blank space thereon. The cutting cylinders 17, 18 divide this web into printed and blank sheets.

In machines embodying the invention, means will be provided for associating the printed sheets of the web 4 with the printed sheets cut from the other web. While this mechanism may be varied, in the particular constructions illustrated, there is employed a transfer cylinder 19, this cylinder being located between the cutting cylinder 18 and the collecting cylinder 13. This transfer cylinder will be provided with sheet taking devices, as, for instance, pins, indicated at 20. In the particular machine illustrated, the cutting cylinder 18 is also provided with sheet taking devices, as, for instance, pins 21, 22. The cylinders 18, 19 are, as shown, of the same size and the sheet taking devices 20 are arranged to co-operate with the sheet taking devices 22. In the operation of this

mechanism,—it being understood that the cutting cylinders are arranged to produce sheets equal in length to half the circumference of the cylinders 18, 19—it is apparent 5 that the head of one sheet will be taken by the pins 21 on the cylinder 18 and that the head of the next sheet will be taken by the pins 22. As the construction is illustrated in Figs. 1 and 2, the pins 22 will deliver 10 the sheets taken by them to the pins 20 on the cylinder 19, but the pins 21 will carry the sheets taken by them around the cylinder 18. In the operation of the machine illustrated, the sheets taken by the pins 21 15 are the blank sheets referred to and these sheets will be delivered out of the machine by any suitable mechanism. In the construction illustrated, there is employed a delivery cylinder 23 having sheet taking devices 20 which may consist of pins 24 and a fly 25. To give the fly time to operate, the cylinder 23 may be arranged to make several revolutions, so as to collect a number of blank sheets before delivering them to the fly. 25 The sheets taken by the pins 20 are forwarded for association with the sheets cut from the web 5. It has been before stated that the cylinder 13 is a collecting cylinder and this cylinder is provided with sheet taking devices which may consist of the usual pins, 26. The mechanism is so timed that these pins, after taking the leading edge of the web 5 carry it around, the pins meeting and taking the sheet held by the pins 20. 30 The sheet carried by the cylinder 19 is thereafter superposed upon the sheet carried by the cylinder 13, the heads of the sheets being carried around and meeting the leading edge of the web 5, as is common in this class of 35 devices. The product is then, where a ten page paper is to be produced, delivered in any suitable manner, though practically the delivery can best be effected by a longitudinal folder of the usual type, such as that 40 indicated at 27. Inasmuch as the sheets from the web 5 are, as has been indicated, four page sheets, and the sheets from the web 4 two page sheets, a ten page product will be formed with the two page sheet inset 45 between the four page sheets. 50

The construction illustrated in Figs. 3 and 4 is arranged to produce a fourteen page product. In this construction, the web 1, instead of being a three wide web, is the 55 full width of the couples, so that the webs 4, 5 are, after being operated upon by the slitter, double wide webs. Inasmuch, however, as a fourteen page product is to be produced, a section will be removed from 60 the side of one of the webs, this necessitating, in the particular machine shown, a cut extending longitudinally of one of the webs. The sheet removing mechanism should, therefore, include means for effecting this longitudinal cut. While this cutting mechanism

may be varied in its details of construction, in the particular construction shown in Figs. 3 and 4, the cutting cylinders 17, 18 are retained, but the mechanism includes an additional cutting mechanism which may be of the slitter type. As illustrated, this mechanism includes a roll 28 with which coöperates a slitter 29, this slitter being mounted on an arm 30 supported on a shaft 31. The arm 30 has connected to it a cam rod 31' 70 forked at its lower end, as 32, to straddle a shaft 33 on which a cam 34 is mounted which coöperates with a roll 35 mounted on the rod 31', the mechanism being a well-known one. The rod 31 may be surrounded 75 by the usual spring 36.

The slitter 29 is shown as operating upon that part of the web 1 which is to form the web 4, and, for clearness of illustration, is shown as located so as to act on the web in 80 advance of the slitter 2, which operates as before. Practically, however, this slitter would usually be arranged so as to coöperate with the roll 3 instead of coöperating with the roll 28. In the construction illustrated, 85 this slitter is arranged to operate between what will become the edges of the web 4, and the cam is timed so that the slitter may produce a cut equal in length to a page. After being slit by the two slitters, in the 90 manner described, the web 4 is, by means of the rolls 15, 16, or equivalent devices, forwarded to the cutting mechanism 17, 18, referring to the particular machine illustrated 95 in Figs. 3 and 4. The knives on the cylinders 17, 18 are only equal in width to the width of a page, so that as the web 4 passes these knives, cuts are made therein which complete the cutting out of a section from the web, as shown in Fig. 6, the section being equal in size to a page, the longitudinal cut which assists in forming this section having been made, as pointed out, by the slitting mechanism 28, 29. The head of this cut-out page section is taken by the pins 21, 100 as before, and it is thereafter carried around the cylinder 17 and delivered to the cylinder 23. The pins 22 which were employed in connection with the cylinder 18 in the construction illustrated in Figs. 1 and 2, are 105 either omitted or rendered inoperative, and the pins on the cylinder 19 employed in connection with the construction illustrated in Figs. 1 and 2 are also omitted or made inoperative. The leading end of the web 4 is 110 carried around the cylinder 19 and is taken by the pins 26 on the cylinder 13, these pins advancing the leading end of the web until it meets the leading end of the web 5 which has been transferred laterally and guided to 115 the cylinders, as in the construction illustrated in Figs. 1 and 2. The pins 26 holding the leading edge of the web 4,—this being the two-page wide part of the web,—as 120 has been described, pick up the leading edge 125

130

of the web 5, and both webs will be carried around the cylinder 13, as indicated in Fig. 3. The pins 26 of the cylinder 13 again impale the web 4, the pins striking across the 5 narrow part of the web, as illustrated in Fig. 6, that is to say, across the part from which the blank sheet before referred to has been removed. As the cutting and collecting cylinders 13, 14 continue their movement, 10 the plies wrapped around the cylinder 13 are cut by the cutting mechanism on the cylinders 13, 14, and after the cutting takes place, the pins pick up the leading edge of the web 5 and advance it for a short distance, after which the pins are withdrawn 15 and the three sheets and that part of the web 5 which forms the fourth sheet are sent to the former. The cylinder 13 continues its revolution with no sheets thereon, until 20 the pins thereon again pick up the leading edge of the web 4. After thus picking up the leading edge of the web, the cylinder continues its revolution until the cutting knives on the cylinders 13, 14 cut off that 25 part of the web 5 which underlies the sheets which have been delivered, thus completing the product which is traveling down the former, and the leading edge of this web is again picked up by the pins; the cycle of 30 operations being continued.

It will be understood that the product going down the former consists of three four-page sheets, and a two page sheet. Referring to the sheets as they go down the former, the top sheet is a four page sheet obtained from the web 4, the second sheet is a four-page sheet obtained from the web 5, the third sheet is a two-page sheet formed by the narrow part of the web 4 (referring to Fig. 6) and the fourth sheet is a four page sheet obtained from the web 5.

It is apparent that by cutting out the slitter 28, 29 and rendering the knives on the cylinders 17, 18 inoperative, a sixteen page 45 paper may be obtained. The machine is, therefore, capacitated to produce all products up to sixteen pages, the pages varying by twos. Furthermore, this may be done with a single set of printing and perfecting cylinders, each cylinder being four plates wide. Further, by reason of the fact that the columns of the plates are arranged to run 50 around the cylinders, the size of the pages may be varied by reducing or increasing the 55 number of columns in the paper, as desired, and the sheets may be folded on a former or longitudinal folder.

Reference has been herein made to the 60 section cut out of the web as a "blank" sheet. It will of course be understood that, if desired, this sheet may be a printed sheet bearing matter which it is not desired to include with the collected product.

Changes and variations may be made in 65 the constructions by which the invention is

carried into effect. The invention is not, therefore, to be confined to the particular constructions herein shown and described.

What is claimed is:

1. The combination with means for forwarding a plurality of webs at the same speed, said webs having been printed on a rotary printing mechanism the printing cylinders of which have their printing surfaces arranged thereon so that the columns run 70 around the cylinders, whereby the webs are imprinted with columns parallel to the run thereof, of a collecting cylinder for collecting sheets cut from one of the webs, and means for removing a section from one of 75 the webs before collection, whereby a product having a number of pages in a multiple of two may be formed.

2. The combination with means for forwarding a plurality of webs at the same speed, the webs bearing printed matter the columns of which are parallel to the run of the webs of a collecting cylinder for collecting sheets cut from the webs, means for removing a section from one of the webs before collection, whereby the cylinder is caused to collect a product the pages of 80 which are not a multiple of four, and a longitudinal folder which receives the product from the cylinder.

3. The combination with means for forwarding a web, said web having been printed on a rotary printing mechanism the printing cylinders of which have their printing surfaces arranged thereon so that the columns run 95 around the cylinders, whereby the web is imprinted with columns parallel to the run thereof, of means for slitting the web, means for thereafter advancing both parts of the web at the same time, means for transferring a part of the web sidewise, a collecting cylinder for collecting sheets from both parts of the web, and means for removing a section from one of the parts prior to collection, whereby a product 100 may be formed the pages of which are not a multiple of four.

4. The combination with means for forwarding and slitting a web, the web bearing printed matter the columns of which are parallel to the run of the web, of means for thereafter advancing both parts of the web at the same speed, means for transferring a part of the web sidewise, a collecting cylinder 115 collecting sheets from both parts of the web, means for removing a section from one of the parts prior to collection, whereby a product may be formed the pages of which are not a multiple of four, and a longitudinal folder which receives the product from 120 the cylinder.

5. The combination with a collecting cylinder, of means for directing a web thereto, a pair of cutting cylinders, means for directing a web to said cylinders, said webs bear- 125

ing printed matter the columns of which are parallel to the run of the webs, a transfer cylinder located between the collecting cylinder and one of the pair of cutting cylinders, sheet taking devices on one of the cutting cylinders arranged to take alternate sections of the product formed by the cutting cylinders, sheet taking devices on the transfer cylinder arranged to forward the remainder of the product formed by the cutting cylinders to the collecting cylinder, and means for delivering the sections taken by the cutting cylinder out of the machine.

6. The combination with a collecting cylinder, of means for directing a web thereto, a pair of cutting cylinders, means for directing a web to said cylinders, said webs bearing printed matter the columns of which are parallel to the run of the webs, a transfer cylinder located between the collecting cylinder and one of the pair of cutting cylinders, sheet taking devices on one of the cutting cylinders arranged to take alternate sections of the product formed by the cutting cylinders, sheet taking devices on the transfer cylinder arranged to forward the remainder of the product formed by the cutting cylinders to the collecting cylinder, means for delivering the sections taken by the cutting cylinder out of the machine, and a longitudinal folder which receives the product from the collecting cylinder.

7. The combination with means for forwarding a web, said web having been printed on a rotary printing mechanism the printing cylinders of which have their printing surfaces arranged thereon so that the columns run around the cylinders, whereby the web is imprinted with columns parallel to the run thereof, of means for slit-

ting the web, means for transferring one part of the web sidewise, a collecting cylinder, means for advancing both parts of the web to the cylinder, and means for removing a section from one of the parts of the web before it reaches the collecting cylinder.

8. The combination with means for forwarding and slitting a web, said web bearing printed matter the columns of which are parallel to the run of the web, of means for transferring one part of the web sidewise, a collecting cylinder, means for advancing both parts of the web to the cylinder, means for removing a section from one of the parts of the web before it reaches the collecting cylinder, and a longitudinal folder which receives the product from the collecting cylinder.

9. The combination with means for forwarding and slitting a web, said web bearing printed matter the columns of which are parallel to the run of the web, of means for transferring one part of the web sidewise, a collecting cylinder to which one part of the web is led, a pair of cutting cylinders to which the other part of the web is led, a transfer cylinder intermediate the cutting and collecting cylinders, means for causing the transfer cylinder to deliver a part of the product formed by the cutting cylinders to the collecting cylinder, and means for delivering the remainder of the product formed by the cutting cylinders out of the machine.

In testimony whereof, I have hereunto set my hand, in the presence of two subscribing witnesses.

LOUIS A. SCHMIDT.
